Primary Examiner — George D. Kirschbaum

CLAIM

The ornamental design for a tile game rack, as shown and described.

DESCRIPTION

FIG. 1 is a perspective view of a tile game rack showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof; and

FIG. 8 is a bottom plan view thereof.

FIG. 9 is an exploded perspective view of the tile game rack; and,

FIG. 10 is another exploded perspective view thereof.

The broken lines depict portions of the tile game rack that form no part of the claimed design.
